(57) **CLAIM**

The ornamental design for a motorcycle engine clutch rod, as shown and described.

DESCRIPTION

FIG. 1 is a front perspective view of a motorcycle engine clutch rod showing my new design;

FIG. 2 is a back view of the motorcycle engine clutch rod shown in FIG. 1; and,

FIG. 3 is an end view, shown enlarged for ease of illustration, of the motorcycle engine clutch rod shown in FIG. 1, with the understanding that both ends are identical.

1 Claim, 1 Drawing Sheet
